UNITED STATES PATENT OFFICE.

EMANUEL FLECK AND JOHN BOYD, OF LA GRANGE, INDIANA.

CARRIAGE-TOP.

SPECIFICATION forming part of Letters Patent No. 248,440, dated October 18, 1881.

Application filed September 2, 1881. (No model.)

To all whom it may concern:

Be it known that we, EMANUEL FLECK and JOHN BOYD, of La Grange, in the county of La Grange and State of Indiana, have invented 5 a new and Improved Attachment for Adjusting Carriage-Tops, of which the following is a full, clear, and exact description.

The object of our invention is to provide a new and improved attachment for facilitating, 10 raising, and lowering of a carriage or buggy top by the person occupying the seat of the buggy or carriage.

The invention consists in a hand-lever pivoted to the end of the seat or railing, and provided with a pivoted locking-lever having at 15 its lower end an eccentric resting against the edge of a semicircular plate attached to the end of the seat or railing, to which hand-lever a jointed lever is pivoted, which has its other 20 end attached to a rod connecting the jointed braces of the buggy-top, whereby, when the hand-lever is turned toward the back of the seat the jointed braces will be folded and the carriage-top lowered.

25 In the accompanying drawings, Figure 1 is a side elevation of a buggy-top provided with my improved attachment for lowering and raising it. Fig. 2 is an enlarged side or longitudinal elevation of the attachment and part of 30 the top, showing the same lowered. Fig. 3 is a plan view of the attachment.

Similar letters of reference indicate corresponding parts.

A hand-lever, A, is pivoted to the end of the 35 seat B, and to this hand-lever A, a locking-lever, C, is pivoted, provided at its lower end with an eccentric, D, resting on a semicircular plate, E, fastened to the end of the seat B. A spring, F, presses the locking-lever C from the 40 hand-lever A. A jointed lever, G, is pivoted at one end to the lever A, and the other end is attached to the cross-bar H, connecting the jointed cross-bars J of the buggy or carriage top R, which is of the ordinary construction, 45 with three bows, L¹ L² L³, and is pivoted to the end of the seat B. The center of the semicircular plate E must correspond with the pivot of the lever A.

The operation is as follows: As long as the

locking-lever C is pressed from the lever A by 50 the spring F the top cannot be folded, for the eccentric D will catch on the edge of the semicircular plate E, and will lock the lever A in position, and will thus prevent the top from being folded as the jointed brace-rods J are 55 united with the hand-lever, and if the latter is locked the jointed brace cannot be folded; but if the top K is to be folded, the locking-lever C is drawn toward the lever A, as shown in Fig. 2, whereby the eccentric D will be disengaged from the edge of the semicircular plate E, thus permitting the hand-lever A to be operated. If this hand-lever A is turned in the direction of the arrow a' the cross-rod H and the lower section of the braces J will 60 be turned in the same direction and the top will be folded. By turning the lever A in the inverse direction the jointed brace-rod will be straightened and the top K raised. As soon as the lever C is released it locks the lever A 65 in position, and consequently the top K will be held in the position it had at the time.

The top can be folded to admit a person into the vehicle, or it may be folded half-way or entirely by simply operating the lever A more 70 or less.

Having thus described our invention, we claim as new and desire to secure by Letters Patent—

1. In a carriage-top, the combination, with 80 the jointed brace-rod J, of the jointed lever G, the hand-lever A, the locking-lever C, and the semicircular plate E, substantially as herein shown and described, and for the purpose set forth.

2. In a carriage-top, the combination, with 85 the jointed brace-rod J, of the jointed lever G, the hand-lever A, the locking-lever C, provided with an eccentric, D, the spring F, and the semicircular plate E, substantially as herein shown and described, and for the purpose set forth.

EMANUEL FLECK.
JOHN BOYD.
